UNITED STATES PATENT OFFICE.

CHARLES S. STICKLE, OF PEKIN, ILLINOIS.

HARVESTER.

SPECIFICATION forming part of Letters Patent No. 293,202, dated February 5, 1884.

Application filed June 22, 1882. (No model.)

To all whom it may concern:

Be it known that I, CHARLES S. STICKLE, of Pekin, in the county of Tazewell, and in the State of Illinois, have invented certain new and useful Improvements in Harvesters; and I do hereby declare that the following is a full, clear, and exact description thereof, reference being had to the accompanying drawings, and to the letters of reference marked thereon, 10 making a part of this specification.

This invention relates to certain improvements in that class of harvesters known as "headers;" and it has for its objects to provide means whereby the forward end of the machine, or that portion which carries the sickle-frame, may be elevated and lowered, and whereby the elevator-frame may be adjusted. It has also for its objects to provide an improved elevator and a new arrangement of 15 belts therefor, and mechanism for operating the same, as more fully hereinafter specified. These objects I attain by the means illustrated in the accompanying drawings, in which—

Figure 1 represents a plan view, partly in section, of my improved machine, the elevator-frame and the arms of the reel being removed; Fig. 2, a side elevation thereof, having the reel-frame and its arms attached and the elevator-frame removed; Fig. 3, a partial side view, 20 showing the carrier-frame, the reel, its frame, and the elevating and adjusting devices. Fig. 4 represents an elevation, partly in section, of the elevator, and a portion of the carrier-frame, showing the mechanism for operating the belt-moving rollers; Fig. 5, a side elevation of portions of the elevator and carrying-frames, 25 showing the means of connecting the two at one side. Fig. 6 is a side elevation, showing the vertical standards and adjustable axle-bearings of the machine. Fig. 7 is an elevation, 30 showing a detached view of the cross-bar, having bearings for the axles. Fig. 8 is a top view, enlarged, of a portion of the machine, showing the gearing for transmitting motion from the driving-wheel to the working parts of the machine; Fig. 9, a plan view of the slatted spring-frame of the elevator detached; and Fig. 10, a sectional view, showing 35 a portion of the frame in section and side elevation, and also showing the bar and its

pivoted rod for elevating and lowering the forward portion of the machine.

The letter A indicates a transverse bar, and B the tongue rigidly secured thereto, the machine being of that class in which the cutting 55 and conveying mechanism are forward, instead of at the rear, of the animals. The said transverse bar has, near each end, on the lower side, boxes or bearings C C, in which are journaled the short axles C' C' of the wheels D. 60 These axles project beyond the ends of the said transverse bar, and set between the standards E E, which are secured to the main frame F of the machine. The said frame consists of two bars, F and F', secured at their forward 65 ends to the transverse bar F², and at their rear ends to a transverse bar, H, located immediately below the bar A, before mentioned, as shown in Figs. 2 and 7.

The letters F' and F' indicate two diverging 70 bars, secured at their forward ends to the bars F, and near their rear ends where they converge to the transverse bar H, as seen in Fig. 10, above alluded to.

The carrier-frame, indicated by the letter 75 K, is mounted upon and secured to the bars F' F and F' F', as shown in Fig. 1.

The letter G indicates the curved bar secured to the under side of the transverse bar H, as shown in Fig. 10, and between the converging ends of the bars F' F', as shown in Fig. 1. The curved bar has pivoted to its rear end a short rod, L, which is also pivoted to a lever, M, which is fulcrumed between standards N, secured to the tongue B. The lever 80 extends backward, and is provided with a keeper, R, between which and said lever passes a rack-bar, S, which is pivoted to the tongue at its lower end. The keeper is provided with a spring-latch, T, from which extends backward a rod, U, which is connected with a small lever, V, by means of which the latch may be operated, to permit the lever M to be raised or lowered in order to adjust the main frame. The carrier-frame is provided 85 with rollers W at each end, around which passes an endless carrier-belt. 90

The letter A' indicates the elevator-frame, which is pivoted to the shaft B' of the lower roller, Z', of the elevator-frame. This shaft 95 100

has its bearings in the sides of the elevator-frame. The lower end of the elevator-frame, at one side, is provided with an open slot, which sets over one end of the roller-shaft B', and is held thereon by means of a curved plate, C', which may be removed to permit the elevator-frame to be removed when required. To the shaft of said roller is secured, by means of a universal joint, D', one end of a shaft, E', the other end of which is secured by means of a universal joint, F', to a short shaft, G', journaled in bearings in a frame, H', attached to the main frame. The shaft G' is provided with a pinion, I', which intermeshes with a gear-wheel mounted on a shaft journaled in bearings K' L' on the frame H'. The said shaft is provided with a beveled pinion, which intermeshes with a beveled-gear wheel on the inner face of the hub of the driving-wheel. The pinion turns freely on the shaft, and the shaft is provided with a sliding clutch, I', which is operated by a lever, K', pivoted at K', and having a rod, L', extending backward to the lever M', fulcrumed at m' to the standard M', by means of which the clutch may be shifted so as to drive or not drive. The shaft B' of the lower roller, Z', of the elevator is provided with a sprocket-wheel, N', from which passes an endless driving-chain to a similar sprocket-wheel on the shaft of the roller W of the carrier-belt, in order to give motion to the same. At the upper end of the elevator-frame is a roller, P', over which and the lower roller extends the elevator-belt R'. The elevator-frame is also provided with rollers S' and T', over which passes a suitable carrier-belt, S'. The shaft of the roller T' is provided with a sprocket-wheel, V', from which extends an endless driving-chain, W', to the sprocket-wheel Z' on the shaft B' of the lower elevator-roller. The said chain is held to the sprocket-wheel V' by means of a sprocket-wheel, A', mounted on a short shaft at the side of the elevator-frame.

The letter B' indicates a yielding slatted spring-frame, rigidly secured at one end to a fixed bar, C', the said frame setting in the upper part of the elevator-frame, so as to press the grain as it is carried up and insure the delivery of the same, a cross-piece, B', being secured to the elevator-frame, to limit the yield of the said slatted frame. The short carrier-belt S', at the lower end of the elevator, insures the proper travel of the grain when delivered from the platform-carrier.

The letter D' indicates a bar secured to the main frame, and to a standard, E', by a pin or

bolt, e', from which extends a rope or chain, connecting with the elevator-frame, and holding it in the proper elevated position.

The letter G' indicates a standard similar to the standard E'. These standards are secured to the carrier-frame, as indicated. The letter H' indicates arms secured, one to the bar I' and to the standard G', and the other to the bar D' and standard E', carrying at their forward ends the reel M'. The rear ends of the arms H' are provided with segmentally-slotted plates N', through which pass the set-screws P', extending into the standards, by means of which the reel may be adjusted. The finger-bar is attached to the forward edge of the carrier-frame, and the sickle is operated by means of any suitable gearing.

The operation of my invention is as follows: The animals are secured to the rear end of the tongue as usual in this class of machines. By throwing the driving-gear into engagement by the means before mentioned the respective belts are put in motion, the carrier delivering the material cut by the sickle and reeled onto said carrier by the reel to the elevator-belts, by which it is carried upward, the slatted frame pressing it closely to the lower belt at its upper end, so as to insure its delivery.

Having thus described my invention, what I claim and desire to secure by Letters Patent, is—

1. The combination, in a harvester, of the transverse bars F' K, the side bars, F, the converging bars F', the upright standards carrying the adjustable bearings, and secured to the bars F, the tongue B, the transverse bar A, the fixed bearing secured thereto, and short independent axles carried in said bearings, substantially as specified.

2. The combination, in a harvester constructed substantially as described, of the transverse bars F' K, the converging and rearwardly-extending bars F' F', the curved bar G, the tongue, the tilting lever having a keeper and a spring-catch, and fulcrumed between the standards secured to the tongue, the ratchet attached to the tongue, and the rod connecting the lever with the curved bar, as and for the purpose specified.

In testimony whereof I affix my signature, in presence of two witnesses, this 28th day of April, 1882.

C. S. STICKLE.
